PRINTED FABRIC AND METHOD OF
MAKING SAME

Duncan Ferguson, New Haven, Conn., and Herbert H. Schell, Garden City, N. Y., assignors to Sidney Blumenthal & Co., Inc., New York, N. Y., a corporation of New York

Application September 1, 1934, Serial No. 742,386

7 Claims. (Cl. 91—67.9)

This invention relates to a printed fabric and method of making same, and more particularly to a pile fabric in which a semi-visible design appears on the front or face of the fabric but not on the pile thereof, the method including printing a design on the back of a pile fabric and subsequent coating of the back with a layer which will protect the printing and firmly embed the pile.

10 It has been known to the art how to back a pile fabric with a layer which will firmly embed the pile, and pile fabric has been printed upon its surface, but so far as we are aware no process of making a semi-visible design on the face 15 by printing upon the back and subsequent coating of the back has before been known.

An object of our invention is to provide a reinforced fabric printed on its back so that only a light design shows through the pile face.

20 Another object of our invention is to provide a reinforced pile fabric having a design on the ground fabric but not on the pile, so that no matter how badly worn the pile may become, the design will remain unchanged.

25 Another object is to provide a reinforced pile fabric suitable for automobile upholstery and like uses having a peculiar semi-visible design due to the fabric bearing a design which may be different from the design on the pile.

30 Still another object is the providing of certain improvements in the form and method of production of a fabric whereby the above named and other objects may effectively be obtained.

35 A practical embodiment of the invention is represented in the accompanying drawing, in which

Fig. 1 represents a front elevation of such a roll as may be used to apply the printing to the fabric, showing in section a piece of fabric passing thereunder;

Fig. 2 represents diagrammatically a back view of a piece of the fabric; and

Fig. 3 represents diagrammatically a face view of a piece of the fabric.

40 The roll by means of which printing is applied to the back of the fabric is designated 1, and is preferably a chromium plated copper roller which is engraved to a depth sufficient to insure the penetration of the printing composition through the back of a pile fabric but no further, in accordance with understood principles of textile printing.

45 Passing under the roller 1 in Fig. 1 is shown an uncoated pile fabric having its backing fabric

portion designated by the numeral 2 and its pile portion designated by the numeral 3.

As shown in Fig. 2, the fabric, after being printed, bears a clear-cut and distinct design 4 on its back or reverse surface, and this appearance is not materially altered by the treatment of said surface with a binding coating of any usual character.

Viewed from the front or pile face, however, as shown in Fig. 3, the pile 3 partially obscures the 10 design 5, giving it a very attractive softness which may be described as "semi-visibility".

In printing the design on the back of the fabric a suitable composition has been found to consist of mixed or pure pigments, and a binding 15 agent capable of affixing the pigment to the fibers of the fabric and having a resistance to water sufficient to withstand the processes of scouring, dyeing, etc. This binding agent may be, for example, emulsified rubber, in either a 20 vulcanized or unvulcanized state, or a solution of nitrocellulose, cellulose acetate or other ester, alginates, or other gums capable of being rendered insoluble, or a varnish, or a combination 25 of the foregoing.

Immediately after printing the fabric, it is subjected, without previous drying, to a coating process with either a rubber solution or some other binder such as, for instance, nitrocellulose lacquer, cellulose acetate, or other ester, or gum lacquer or varnish. The cloth is then thoroughly dried. In case rubber has been used as the binding agent, it is at least partially vulcanized during this drying operation.

The product may then be scoured, dyed, printed on its face, and further processed without injury either to the design on the fabric or to the backing, and with a minimum loss of pile threads.

It will be understood that various changes 40 may be resorted to in the form and production of this fabric without departing from the spirit and scope of our invention, hence we do not intend to be limited to the details herein shown and described except as they may be included in 45 the claims.

What we claim is:

1. The method of making a pile fabric which includes, applying a design to the flat side by printing thereon, causing the printing composition to show through on the pile face of the backing fabric without affecting the projecting portions of the pile, coating said flat side with a binder, and drying the material.

2. The method of making a pile fabric which

includes, applying a design to the flat side by printing thereon with a composition including a coloring material and a binding material, causing the printing composition to show through on the pile face of the backing fabric, without affecting the projecting portions of the pile, coating said flat side with a binder, and drying the material.

3. The method of making a pile fabric which includes, applying a design to the flat side by printing thereon with a composition including a coloring material and a binding material, causing the printing composition to show through on the pile face of the backing fabric without affecting the projecting portions of the pile, coating said flat side with a binder, drying the material and applying another design to the pile.

4. A printed pile fabric having a design printed on its flat side and appearing less distinctly

on the pile side, and a binding coating intimately engaged with said fabric on its flat side.

5. A printed pile fabric having a design printed on its flat side and appearing less distinctly on the pile side, said design being confined to the 5 backing portion of the fabric without affecting the projecting portions of the pile.

6. A printed pile fabric having a design printed on its flat side and appearing less distinctly on the pile side, said design being confined to the 10 backing portion of the fabric without affecting the projecting portions of the pile, and a binding coating intimately engaged with said fabric on its flat side.

7. A printed pile fabric having a semi-visible 15 design printed on its backing portion and a different design on its pile portion.
